FUR CLEANING MACHINE

Nathan Root, Grand Rapids, Mich.

Application April 7, 1945, Serial No. 587,121

10 Claims. (Cl. 69—23)

This invention relates to a fur cleaning machine, sometimes referred to in the trade as a "fur drum." It has more particular reference to a machine adapted to the cleaning of garments comprising animal fur, wherein the garment is tumbled in a rotating drum in the presence of specially compounded cleaning materials, usually wood sawdust impregnated or combined with suitable solvents and/or detergents.

In the cleaning of fur garments the method commonly utilized is to place the garments loosely in a drum adapted to be rotated relatively slowly, and to cleanse the fur while therein by the action of a mixture of sawdust combined or impregnated with a suitable solvent and/or detergent. By thus tumbling the garments and sawdust, the latter acts to carry the cleansing materials deeply into the pelt and to retain them in intimate contact with the hairs and skin until sufficient time has elapsed for thorough cleansing to have occurred.

To be efficacious, the prepared sawdust must be maintained in cleansing contact for the predetermined period of time, and following the cleansing the sawdust must be thoroughly shaken out of the garment. Prior machines have attained this end in three ways. First there is the class of machines comprising two independent drums, one being closed except for a loading door, and in which the sawdust and garments are tumbled. The machine is then stopped and the garments transferred from that drum into the second, or perforate drum, wherein they are tumbled to remove residual sawdust. Thus, not only must the machine be stopped, but the garments carried manually from one drum to the other. In the second class of machines there is employed a single perforate drum rotating within a casing. The sawdust is delivered to within the drum by scoops rotating therewith to lift sawdust from the drum casing and to drop the same through the drum. The sawdust is intended to perform its function while passing from the point of delivery above to the lowest point of the drum whereat it is sifted out through the perforations and into the casing. Removal of residual sawdust is accomplished by rotating the drum while the scoops are manually put out of action. Thus the second class of machines suffers from its inability to retain the sawdust within the drum sufficiently long to yield a thorough cleansing action. The third class of machines utilizes a single cylindrical drum having a peripheral opening. During cleaning the opening is covered by a solid panel manually slid into place over the

opening. For disposal of the sawdust following the cleaning phase the machine is stopped, the solid panel removed, and a screen inserted in place thereof, whereby upon further tumbling the sawdust is shaken out through the screen.

In one form of the machine of my invention only one drum, together with a concentric shutter, is utilized. The drum is provided with a plurality of peripherally spaced, screened openings, and the shutter is provided with a plurality of leaves equal in number to the number of openings, and the shutter is adapted to be operated so that in the cleansing phase the leaves block the screened openings to retain the sawdust in the drum, but when "shaking out" is to be accomplished the operator may quickly position the shutter with its leaves out of register with the openings, and upon further rotation the sawdust is shaken out through the screened openings to a container disposed below. Repositioning of the shutter leaves for a subsequent batch is immediately accomplished irrespective of whether the drum is rotating.

Accordingly, the principal object of my invention is the provision in a fur-cleaning machine utilizing sawdust or similar particulate material capable of the same use in fur-cleaning, and with or without solvents and detergents, of a single drum for both cleaning and shaking-out and instantaneously convertible from a cleaning drum to a drum for shaking out the particulate material from the fur.

Still a further object is the provision in a fur-cleaning machine of a drum and a shutter revoluble therewith, the drum having a plurality of screened openings in the periphery thereof and the shutter having an equal plurality of leaves adapted to block said openings or to expose them.

Another object is the provision of a drum and shutter cooperative therewith as aforesaid, the drum and shutter being adapted to rotate as a unit, and the shutter being operable at selected intervals under the control of the operator to position the shutter in screen-blocking or screen-exposing positions.

A further object is the provision of manual means for actuating the revolving shutter with respect to the revolving drum into screen-blocking or screen-exposing positions, the said means being stationary.

Another object is the provision of resilient driving connections between the shutter and the drum so that upon actuation of the manual means aforesaid, the shutter changes from screen-

exposing to screen-blocking position instantaneously.

Other objects will appear as the description proceeds.

In the drawings, which show one preferred form of my invention,

Fig. 1 is a side elevational view of the machine;

Fig. 2 is a rear elevational view of the machine;

Fig. 3 is a cross section taken on the line 3—3 of Fig. 2;

Fig. 4 is a cross section taken on the line 4—4 of Fig. 3;

Fig. 5 is a cross section taken on the line 5—5 of Fig. 2 and showing the shutter in screen-exposing position;

Fig. 6 is a cross section taken on the line 6—6 of Fig. 4;

Fig. 7 is a cross section taken on the line 7—7 of Fig. 4;

Fig. 8 is a view similar to that of Fig. 3 but of an alternative form of the invention; and

Fig. 9 is a view similar to that of Fig. 4 but of the form of the invention shown in Fig. 8.

In the several views some parts have been shown broken away for clarity.

Referring to Fig. 1, the machine comprises a rectangular base 10 to which is secured by any suitable means the casing 11 comprising front and rear panels 12 and 13, respectively, having inturned base flanges 14 and 15, respectively, for securing the same to the base 10. As more clearly shown in Fig. 4, the panels 12 and 13 each comprise a circular portion extending downwardly into a substantially rectangular portion. Joining the panels 12 and 13 is the peripheral casing portion 16 substantially cylindrical in form and extending downwardly in straight portions to correspond with the contour of the panels 12 and 13. Flanges 17 and 18 serve to secure the portion 16 to the base 10, and the entire casing 11 is welded or otherwise suitably joined to yield a rigid, box-like structure.

Attached as by bolts 21 to the panel 13 is the housing 22 having a cylindrical aperture 23 into which is pressed the pair of anti-friction bushings 24. Adapted to rotate within the bushings 24 is the hollow shaft 25 and integral therewith is the flange 26 attached by means of rivets 27 to the shutter 28. The shutter 28 comprises a substantially circular disc 29 having three integral shutter-leaves 32 extending at right angles thereto and attached by means of rivets 33. It will be noted that the leaves 32 are imperforate and extend in a plane concentric with the casing 16. Although three leaves 32 are illustrated, it will be understood from what follows that there may be more or less.

Pressed into the aperture 36 of the hollow shaft 25 is a pair of anti-friction bushings 37 and adapted to rotate within said bushings is the shaft 38 having an integral flange 39 riveted as at 41 to the drum proper 42.

Drum 42 is cylindrical in form and comprises a circular rear wall 43 and an annular front wall 44, there being an aperture 45 in the front wall 44 flanged as at 46 to provide rigidity and a smooth entrance for access to the interior of the drum 42. The cylindrical wall 47 of the drum 42 is provided with a plurality of rectangular openings 51 equal in number to the number of shutters 32, the said openings 51 being filled by a wire mesh screen 52. The size of mesh is relatively unimportant except that it cannot be so large as to damage the garments or so small as to interfere with rapid disposal of

the sawdust during the shaking-out phase of the cleaning operation. Suitably attached to the outer surface of the wall 47 is a plurality of peripherally disposed guides 50 offset as shown in Fig. 3, and between which and the wall 47 the overhung end of each of the shutters 32 is adapted to be retained and guided.

The drum 42 is maintained against axial movement by the engagement of the rear face of the flange 39 with the adjacent face of the hollow shaft 25, as well as by the flanged collar 54 attached by means of a setscrew 55 to the shaft 38.

The wall 43 of the drum 42 carries a pair of pins 141 preferably diametrically opposed to each other and adapted to engage a pair of arcuate slots 142 through the shutter 28. The latter is also provided with a pair of generally arcuate openings 143 also preferably positioned diametrically opposite one another and intermediate the slots 142. Through apertures 144 adjacent one end of the slots 143 are attached springs 145, the opposite end of each spring being attached to a pin 146 carried by the wall 43.

Through the front wall 12 of the casing there is provided an aperture 61 reinforced by a flanged rim 62. Mounted on the panel 12 is a pair of ears 63 upon which is hung the door 64, the arms 65 and pins 66 serving to support the door swingably on the ears 63. The door 64 is preferably circular in form and of sufficient extent to cover the opening 61 and may, furthermore, be provided with a finished face 67 equipped with a gasket, if desired, to provide a tight seal when the door is locked. A suitable handle 71 engaging a catch 72 affixed to the panel 12 serves to lock the door 64.

Interposed between the housing 22 and the collar 54 is the pulley 73, the hub 74 of which carries the setscrew 75 to lock the pulley 73 to the hollow shaft 25. The hub 74 has a circular aperture 76 parallel to the axis thereof and positioned intermediate the bore and periphery of the hub 74, and the collar 54 has an identical aperture 77 spaced the same radial distance from their common center of rotation, but the two apertures are adapted to be brought into register only under certain operating conditions to be hereinafter detailed.

Adapted to swing in the bifurcated end 80 of a support 81 outstanding from the panel 13 is the yoke 82 (Figs. 2 and 5), one end thereof being pivoted on pins 83 adapted to engage apertures in the support 81. Yoke 82 comprises a substantially thin flat member centrally ribbed as at 84 for rigidity, and provided with an enlarged annular portion 85 determining a circular aperture 86. Adapted to travel on the periphery of the aperture 86 is the pin 91 which includes a pair of flanges 92 integral with a straight cylindrical portion 93 slidable within the aperture 77. Thus it will be noted that when the collar 54 is rotated, it may carry with it the pin 91, the latter being constrained to travel a circular path inside of the aperture 86 but being permitted axial movement only upon corresponding movement of the yoke 82.

At its free end the yoke 82 is provided with an aperture 94 to receive the double flanged head 95 of the operating rod 96, the said rod being guided for axial movement in a bracket 97 attached to the panel 13, and threaded engaged in a second bracket 98 affixed to the panel 12. At its forward end the rod 96 is bent to form a crank 99 having a handle 102.

The pulley 73 may be provided with a grooved

periphery, as shown, to receive the driving belt 111 passing around a similar pulley 112 affixed to the shaft 113 of the gear reducer unit 114 of a conventional type which may or may not be an integral part of the electric motor 115. It will be understood that the combination of the gear reducer unit 114 and motor 115 is well known and may be of the kind in which the gear reducer housing is a part of one of the housings of the motor and in which the driving gear is coupled directly to the motor armature, or the gear reducer 114 may be a separately mounted unit the input shaft of which is connected by a suitable coupling to the shaft of the motor. A suitable switch (not shown) serves to start and stop the motor 115.

At the base of the casing 11 is provided a drawer 121 having a front 122, handle 123, and drawer portion proper 124. The drawer 121 is adapted to slide on a pair of angle iron guides 125 mounted on the rectangular bottom stiffening member 126 of the casing 11. A suitable opening 127 is provided in the panel 12 through which the drawer may pass for insertion and withdrawal with respect to the machine. To the inner surface of the lower straight walls of the casing portion 16 there is attached a funnel-shaped spout 147 having its wider upper aperture coextensive with the area intermediate the walls and its lower narrower aperture coextensive with the drawer proper 124.

Preferably the lower straight sides of the peripheral portion 16 of the casing 11 are provided with venting apertures 128 comprising, for example, openings screened by a suitable perforate material. Thus noxious fumes emitted by the detergent material may be vented freely to atmosphere.

To supplement the venting openings 128 there may be provided a motor driven blower 131 carried on a bracket 132 attached by any suitable means on the panel 13. The intake duct 133 of the blower is connected into the top of the peripheral portion 16 of the cabinet as at 134. The exhaust opening 135 of the blower is open to atmosphere. During operation of the machine the motor driven blower 131 will be placed in operation to draw fumes from the machine and exhaust them harmlessly to the outside air.

Operation

In using the machine the door 64 is opened, the fur garments inserted through the openings 61 and 45 and deposited within the drum 42. Then a predetermined amount of the proper cleaning material, for example, wood sawdust impregnated with detergents and/or solvents, is sprinkled over the garments. The door 64 is then locked and the motor 115 and blower 131 started into operation. At this time the yoke 82 is positioned by means of the handle 102 in its rearward position so that the pin 93 is withdrawn from the aperture 76. Accordingly, rotation of the motor 115 will drive the pulley 73 which, through the hollow shaft 36, will drive the shutter 28 in a clockwise direction as viewed in Fig. 4. Thus the trailing end of the slots 142 will engage the pins 141 to rotate the drum 42. It will be noted that in this relative position of the drum 42 and shutter 28 the leaves 32 block the screened openings 52. Consequently the fur garments and cleaning substance are tumbled together within the drum until it is determined that the garments are properly cleaned. During this portion of the process, known in the trade as "drumming," it will be

obvious that the garments and the sawdust are retained within the cabinet in the necessary intimacy of contact, and that the tumbling motion of the garments and sawdust will effect an efficient cleansing action, the fragmentary particles being brought down and around the hairs in a thorough but gentle manner, all as known to the art. While this occurs, any noxious fumes escape through the vents 128 or are exhausted through the duct 133 and fan 131.

At the completion of the drumming phase, the motor 115 is stopped, whereupon the springs 145 will contract to rotate the drum 42 clockwise until the latter is stopped by the pins 141 striking the leading end of the slots 142. Such relative shifting of the drum with respect to the shutter will move the screened openings 52 out from beneath the shutter leaves 32 (Fig. 5) to expose the said openings. The angle subtended by the ends of the slots 142, taking into account the diameter of the pins 141, is equal to the angle between a radial line through the pin 91 and a radial line through the aperture 76 when drumming is being performed. Accordingly, when the drum 42 shifts relatively to the shutter 28 as aforesaid, the pin 91 will be brought into register with the aperture 76. The handle 102 is now turned to actuate the yoke 82 inwardly of the machine to slide the pin 91 into the aperture 76. The motor 115 is again started and the pulley 73 may now, through the pin 91, rotate not only the shutter 28, but the drum 42, and such continued rotation will shake the sawdust out of the drum and garments through the openings 52 and chute 147 and into the drawer 124.

After a sufficient length of time has elapsed for all of the sawdust to be thoroughly shaken out of the garments and from the drum 42, the machine is stopped and the garments removed. The sawdust in the drawer 124 may be re-used as is or blended with fresh material, depending upon the degree of exhaustion of the detergent elements therefrom.

To prepare the machine for the next cycle, the handle 102 is rotated in the opposite direction to withdraw the pin 91 from the aperture 76. Accordingly, when drumming is recommenced the rotation of the shutter 28 will return it to that position relative to the drum 42 shown in Fig. 4, the springs 145 then being extended for as long as the motor is driving.

In Figs. 8 and 9 there is shown an alternative form of the apparatus, the yoke 82, pin 91, hub 54 and their associated parts, as well as the springs 145, being omitted. In this embodiment the motor 115 is of the reversing type provided with a stop-start-reverse switch 151 mounted in any suitable place convenient for the operator.

In this form of the invention drumming occurs with the shutter 28 rotating clockwise, all as heretofore explained. However, when shaking out is to be performed, the motor is reversed by means of the switch 151, and the shutter 28 will then shift angularly with respect to the drum 42, as explained in connection with the principal form of the invention, and by the amount allowed by the slots 142. In that position the shutter 28, instead of driving the pins 141 through the ends of the slots shown in contact therewith in Fig. 9, will drive the pins by contact with the opposite ends of the slots. It will be noted that in such relative driving position of the shutter 28 and drum 42, the leaves 32 expose the openings 52 with the same results as explained in connection with the main embodiment.

Although the description herein is directed to a machine of the type disclosed, in which the drum is rendered shiftable with respect to the shutter when it is desired to transfer from the cleaning phase to the shaking out phase, I desire to include within the scope of the specification and claims a machine so constructed that the shutter may shift relatively to the drum. This could be accomplished, for example, by driving the drum and interconnecting the shutter with the drum through the use of a pin and aperture as already detailed. The gist of the invention lies in the relative shifting of the drum and shutter in order to effectuate the opening and closing of the screened openings, and accordingly it will be understood that this object may be reached if the drum were the driving member and the shutter the driven member, this involving merely a simple reversal of these two principal parts of the apparatus and the necessary slight rearrangement of the remaining parts associated therewith, all of which is deemed within the skill of the art.

While I have shown particular embodiments of my invention, it will be understood, of course, that I do not wish to be limited thereto since many modifications may be made, and I therefore contemplate by the appended claims to cover any such modifications as fall within the true spirit and scope of my invention.

Having thus described my invention, what I claim and desire to secure by Letters Patent is:

1. A cleaning machine adapted to receive fur garments and a particulate cleaning material comprising in combination a supporting structure, a source of power, a hollow cylindrical drum to receive the garments and material and supported for rotation in said structure and having a plurality of apertures therein, a shutter member provided with leaves equal to the number of said apertures and each leaf being at least coextensive with an associated aperture, said member being supported for rotation in said structure, means connecting said source with said member for rotation thereof, means intermediate said drum and member whereby rotation of said member rotates said drum, resilient means intermediate said drum and member normally urging said member and drum in opposite angular directions with respect to each other, and selectively operable means to lock said drum and member with respect to each other whereby driving of said member drives said drum to position said leaves in register with said apertures and interruption of said driving permits said leaves to move out of register with said apertures under urging of said resilient means.

2. A cleaning machine adapted to receive fur garments and a particulate cleaning material comprising in combination a supporting structure, a source of power, a hollow cylindrical drum to receive the garments and material and supported for rotation in said structure, the periphery of said drum having spaced perforate zones, a shutter member provided with leaves equal to the number of said zones and each leaf being at least coextensive with an associated zone, said member being supported for rotation in said structure, means connecting said source with said member for rotation thereof, means intermediate said drum and member whereby rotation of said member rotates said drum, resilient means intermediate said drum and member normally urging said member and drum in opposite angular directions with respect to each other, and selectively operable means to lock said drum and member with re-

spect to each other whereby driving of said member drives said drum to position said leaves in register with said zones and interruption of said driving permits said zones to move out of register with said leaves under urging of said resilient means.

5 3. A machine for drumming and shaking-out fur garments including the use of a particulate cleaning material comprising in combination a frame, a hollow drum to receive the garments and material and supported for rotation in said frame, said drum having a plurality of spaced perforate zones in the periphery thereof, a shutter member having a plurality of elements equal to the number of zones and each element being at least coextensive with an associated zone, the said member being supported for rotation in said frame, and the said elements being adapted to block said zones during drumming, means for driving said member, means intermediate said drum and member whereby said member drives said drum, means for shifting said member and drum angularly with respect to each other, and selectively operable means to lock said drum and member with respect to each other when said drum and member are shifted, the said elements moving out of blocking position upon said shifting, whereby continued rotation of the drum and shutter effectuates shaking-out the material from the garments and drum.

20 4. A cleaning machine adapted to receive fur garments and a particulate cleaning material comprising in combination a frame, a drum to receive the garments and material and supported for rotation in said frame, said drum having a plurality of spaced perforate zones in the wall thereof, a shutter member having a plurality of imperforate elements equal to the number of zones and each element being at least coextensive with an associated zone and said elements being adapted to be operated into and out of register with said zones, said member being supported for rotation in said frame, means for driving said member, means intermediate said drum and member whereby said member drives said drum, means for shifting said shutter and drum angularly oppositely with respect to each other to move said elements into and out of registering position.

25 5. A machine for drumming and shaking-out fur garments including the use of a particulate cleaning material comprising in combination a frame, a container to receive the garments and material and supported for rotation in said frame, said container having a plurality of apertures therein, a member supported for rotation in said frame and having a plurality of apertures, said member during the drumming phase being positioned with its non-apertured portions blocking the apertures in said container and means selectively operable to position the apertures in said member in register with the apertures in said container for the shaking-out phase, and means for rotating said container and member as a unit.

30 6. A machine for drumming and shaking-out fur garments including the use of a particulate cleaning material comprising in combination a frame, a container to receive the garments and material and supported for rotation in said frame, said container having a plurality of apertures therein, a member supported for rotation in said frame and having a plurality of apertures, said member during the drumming phase being positioned with its non-apertured portions blocking the apertures in said container, driving means connected to said member, means intermediate said container and drum whereby rotation of said member is imparted to said drum, resilient means

intermediate said container and drum effective upon termination of rotation of said member to rotate said drum with respect to said member to position the apertures in said drum and in said member in register, and means to lock said drum and container in said last-mentioned position.

7. A machine for drumming and shaking-out fur garments including the use of a particulate cleaning material comprising in combination a frame, a container to receive the garments and material and supported for rotation in said frame, said container having a plurality of perforations therein, a member associated with said container and supported for rotation in said frame and having a plurality of perforations therein, said member during the drumming phase being positioned with its imperforate portions blocking the perforations in said container, driving means connected to said member, said container being provided with a plurality of elements and said member having a like plurality of arcuate openings, the said elements being adapted to engage with said openings to form a driving connection between said member and container, a plurality of elements interconnecting said container and member and normally adapted to bias the member with respect to the container angularly in a direction opposite to the normal joint direction of rotation of the said member and container whereby upon interruption of the rotation of said container and member said container is shifted angularly with respect to said member to effect registration of the said two sets of perforations.

8. A cleaning machine adapted to receive fur garments and a particulate cleaning material comprising in combination a frame, a hollow, cylindrical drum to receive the garments and material and supported for rotation in said frame, a plurality of screened openings in the periphery of said drum, a circular member juxtaposed to one end of said drum and rotatably supported in said frame and having a like plurality of vanes adapted to be positioned to block said openings or to expose said openings, means for rotating said member, said member having a plurality of arcuate slots and said drum having a like plurality of elements each adapted to engage a slot asso-

ciated therewith whereby rotation of said member imparts rotation to said drum, a plurality of resilient elements interconnecting said drum and member, said resilient elements being so proportioned that the inertia of the drum, its associated parts and contents during joint rotation of the drum and member tends to bias the said elements to a stressed condition such that upon interruption of said joint rotation of said drum and member said elements will angularly displace said drum with respect to said member to move the said vanes from blocking position to nonblocking position.

9. A fur cleaning machine adapted to clean furs by the use of a particulate detergent material and to shake out said material after completion of the cleaning phase comprising in combination a rotatable cylindrical drum having a plurality of apertures in the periphery thereof, a shutter member having a like plurality of leaves and adapted to rotate with said drum, said leaves being at least coextensive with said apertures and positioned during the cleaning phase in aperture-blocking position, said drum being adapted to be shifted angularly relative to said shutter, means for imparting rotation to said drum and member, means for actuating said drum relative to said shutter after completion of the cleaning phase to shift said drum and to position said leaves in aperture-exposing position.

10. A fur cleaning machine adapted to clean furs by the use of a particulate detergent material and including a drumming phase and a shaking-out phase comprising in combination a rotatable drum to receive the furs and material and having a plurality of apertures therein, means to rotate said drum, a shutter shiftable relatively to said drum and adapted to rotate with said drum and having a plurality of leaves, each said leaf being associated with a said aperture, said leaves being positioned during the drumming phase to block said apertures and adapted upon such relative shifting of said shutter and drum to expose said apertures for the shaking-out phase, and means for effecting said shifting.

NATHAN ROOT.
